UNITED STATES PATENT OFFICE.

CHARLES ERNEST JONES, OF CHICAGO, ILLINOIS.

DESIGN FOR A CHAIN-SUPPORT FOR CHANDELIER.

50,691.

Specification for Design.

Patented May 1, 1917.

Application filed March 6, 1917. Serial No. 152,939. Term of patent 3½ years.

To all whom it may concern:

Be it known that I, CHARLES ERNEST JONES, a citizen of the United States, residing at Chicago, in the county of Cook and State of Illinois, have invented a new, original, and ornamental Design for a Chain-Support for Chandeliers, of which the following is a specification, reference being had to the accompanying drawing, wherein—

Figure 1 is a side elevation, and Fig. 2 is an inverted plan view of a chain support for chandeliers, showing my new design.

I claim as my invention:
The ornamental design for a chain support for chandeliers, as shown.

CHARLES ERNEST JONES.
